UNITED STATES PATENT OFFICE.

ALFRED H. WILLETT, OF WEST NEW YORK, NEW JERSEY, ASSIGNOR TO AMERICAN ARCH COMPANY, OF NEW YORK, N. Y., A CORPORATION OF DELAWARE.

FIRE-BRICK ARCH AND BRICK THEREFOR.

Application filed December 4, 1919. Serial No. 265,193.

To all whom it may concern:

Be it known that I, ALFRED H. WILLETT, a citizen of the United States, residing at West New York, in the county of Hudson and State of New Jersey, have invented 5 certain new and useful Improvements in Fire-Brick Arches and Bricks Therefor, of which the following is a specification.

This invention has reference to a form of 10 construction in which by the employment of a certain novel formation of reversible and invertible brick an arch may be constructed which will be either perforated or imperforate or in which a portion may be imperforate and various arrangements of the perforations of the remaining portion may be obtained by varying dispositions of the bricks.

The above, as well as other objects as may 20 hereinafter appear, I obtain by means of a construction which I have illustrated in preferred form in the accompanying drawings, wherein:

Figure 1 is a horizontal sectional view 25 through the upper portion of a locomotive fire box showing, in plan, an arch constructed in accordance with my invention; Figure 2 is a longitudinal vertical section through the fire box and arch structure shown in 30 Fig. 1 except that the wing bricks are shown with a modified end where they bear against the side sheet; Figure 3 is a transverse sectional view through a fire box showing the arch structure of Figure 1 in end elevation; 35 Figure 4 is a horizontal sectional view through the fire box showing, in plan view, a modified arrangement or positioning of the bricks; and Figure 5 is a view of one of my improved bricks shown in perspective.

Referring now more particularly to Figs. 1 and 2, it will be seen that I have therein shown a fire box having side sheets 1, a flue sheet 2, a crown sheet 3, an inside rear sheet 4 and a water leg at 5, connected by circulating and brick supporting tubes 6 with the water space 7. Upon the tubes 6 I place the bricks 8 which are shown in detail in Fig. 5 and which have recesses 9 in one horizontal 50 face and oppositely disposed supporting surfaces 10 and 11, the surfaces 10 being preferably inclined as shown, and the surfaces 11 being curved in such manner as will more accurately fit upon the supporting tubes 6. Upon one of the edges of the brick,

I arrange a projection 12 and upon the other a corresponding recess 13, the two being so proportioned and disposed that when the brick is rested in position upon the tubes, as indicated in Fig. 1, either the projections 60 12 will come in contact with each other, leaving apertures adjacent to the tubes, as at 14, and other apertures near the middle of the brick as at 15, or else, where it is desired to close the arch, that is to provide an arch or a 65 portion of an arch which is imperforate, the projections 12 will engage the corresponding recesses 13 in adjacent bricks as indicated at 16 in Fig. 1, and in all of the bricks shown in the arch of Fig. 4. 70

In the arrangement shown in Fig. 1, the major portion of the arch toward the rear is formed with perforations some of which are adjacent to the supporting tubes and others in staggered relation thereto along 75 the middle line of each row of bricks. This disposition of the units or bricks 8 serves to effectually break up the flow of gases or products of combustion traveling upward through the arch and produces uniform 80 heating and combustion effect in the furnace, especially where the rows at the center of the arch are extended a greater distance toward the rear than the wing bricks 17 located at the sides. The wing bricks 17 are 85 preferably arranged as shown in Figs. 1 and 3 being narrower at their outer ends where they bear against the side sheet as indicated at 18 in Fig. 3 and also, if preferred, arranged with an angular end as at 90 19 in Fig. 2.

I claim:

1. A fire brick for arch constructions provided with a projection upon one edge intermediate its ends, said projection extending from one horizontal face to the other, and a correspondingly disposed and formed recess in the other edge, and oppositely disposed end supporting surfaces constructed to engage supporting members and to reversibly or invertibly support the brick whereby the projection on one brick may be made to contact with that on an adjacent brick or whereby the projection on one brick may be made to engage the recess in an adjacent brick. 95

2. A fire brick for arch constructions provided with a projection upon one edge intermediate its ends, said projection extending from one horizontal face to the other, 100 105 110

- and a correspondingly disposed and formed recess in the other edge, and end supporting surfaces constructed to reversibly support the brick whereby the projection on one brick 5 may be made to contact with that on an adjacent brick or whereby the projection on one brick may be made to engage the recess in an adjacent brick, there being formed apertures through the arch when projection 10 engages projection but an imperforate arch when projection engages recess in adjacent bricks.
3. An arch for fire boxes provided with circulation tubes, comprising in combination 15 a plurality of counterpart bricks alternately supported in reversed relation on said tubes, each brick being constructed with a projection on one of its edges intermediate its ends, said projection extending from one horizontal 20 face to the other, and a correspondingly formed and disposed recess in the other edge, said projections abutting to form perforations through the arch adjacent the tubes and said recesses abutting to form 25 perforations through the arch intermediate the tubes, the perforations adjacent the tubes alternating with the perforations intermediate the tubes.
4. An arch for fire boxes provided with circulation tubes, comprising in combination 30 a plurality of reversible counterpart bricks adapted to be supported on said tubes, each

brick being constructed with a projection on one of its edges intermediate its ends, said projection extending from one horizontal 35 face to the other, and a correspondingly formed and disposed recess in the other edge, certain of the bricks being arranged so that projections fit into recesses in portions of the arch to form an imperforate area of 40 arch, other bricks being arranged with projections and recesses abutting to form perforations through the arch adjacent the tubes and intermediate the tubes, said perforations alternating longitudinally of the 45 fire box.

5. A tube-supported arch for locomotive fire boxes having a plurality of perforations therethrough adjacent the tubes and a plurality of perforations intermediate the tubes, 50 said perforations alternating longitudinally of the fire box.

6. A tube-supported sectional brick arch for locomotive fire boxes constructed of a plurality of reversible, counter-part bricks, 55 said bricks being so formed and arranged as to create a plurality of perforations therethrough adjacent the tubes and a plurality of perforations intermediate the tubes, said perforations alternating longitudinally of 60 the fire box.

In testimony whereof, I have hereunto signed my name.

ALFRED H. WILLETT.
